YIELDABLE PNEUMATIC THREAD REMOVER
FOR LOOMSAlexander C. Krukonis, Auburn, Mass., assignor
to Crompton & Knowles Loom Works, Worcester,
Mass., a corporation of Massachusetts

Application March 25, 1950, Serial No. 151,857

6 Claims. (Cl. 139—256)

1

This invention relates to improvements in pneumatic thread removers for looms and it is the general object of the invention to provide a mounting for the remover which will permit it to yield to avoid damage if the shuttle is not properly boxed.

It has been proposed heretofore to mount a pneumatic thread remover adjacent to the reserve bobbin magazine of a weft replenishing loom and move it to thread pick-up position incident to a bobbin changing operation. Such removers are ordinarily in raised position and are depressed by a stud extending laterally from the transerrer arm, and if a shuttle is widely misplaced transfer will be revoked and the thread remover will remain in raised position. In some instances however where the shuttle is only slightly misplaced, the mechanism which is intended to revoke a transfer fails to operate and the thread remover is forced down against the end of the shuttle which protrudes from the shuttle box with resultant damage to both the shuttle and the remover.

It is an important object of the present invention to provide a thread remover which is held yieldingly on a carrier so that as the latter rocks under the action of the transerrer arm the remover can move upwardly with respect to the carrier if it engages the shuttle. The remover is conveniently held in a normal down position with respect to the carrier by resilient means such as a spring and will move with the carrier without relative movement with respect thereto on all normal replenishing operations.

If the carrier, stud on the transerrer arm, and the remover are so related that the latter is likely to be forced downwardly too far so that it strikes the lay the yielding connection between the carrier and the remover will permit a slight upward relative motion of the latter so that it will not be damaged when engaging the lay.

It is a more specific object of the invention to provide the carrier with a vertical guide slot through which the remover tube extends and in which it can have relative guided vertical motions with respect to the carrier. The forward end of the remover is preferably mounted for angular motion with respect to the carrier and the remover tube can slide forwardly relative to the carrier and its pivotal connection in the event that it is struck by a misplaced shuttle as the lay moves forwardly.

With these and other objects in view which will appear as the description proceeds, the invention resides in the combination and arrange-

2

ment of parts hereinafter described and set forth.

In the accompanying drawings, wherein a convenient embodiment of the invention is set forth,

Fig. 1 is a side elevation of one form of weft replenishing mechanism having the invention applied thereto, the lay, shuttle box, shuttle and part of the loom frame being shown in cross section,

Fig. 2 is an enlarged plan view looking in the direction of arrow 2, Fig. 1,

Fig. 3 is a detailed vertical transverse cross section on line 3—3, Fig. 2, showing that part of the carrier which provides a vertical guide for the remover tube,

Fig. 4 is an enlarged vertical transverse section on line 4—4, Fig. 2, showing the pivotal mounting for the forward end of the thread remover tube,

Fig. 5 is a reduced vertical section on line 5—5, Fig. 4, and

Figs. 6 and 7 are diagrammatic views showing two types of yielding of the remover when it engages a misplaced shuttle.

Referring particularly to Fig. 1, the loom frame 10 has mounted thereon a support 11 provided with a pivot pin or stud 12 on which a reserve bobbin magazine M is mounted. The magazine as set forth herein is of the type which carries two stacks of reserve bobbins (not shown) and is rocked so that the lowest bobbin in one or the other of the stacks will be in transfer position. Ordinarily the magazine is at rest and transfer from one stack will occur without rocking of the magazine, but transfer from the other stack requires a slight angular motion of the magazine.

The support 11 carries a transerrer stud 15 on which the transerrer arm 16 is pivoted. This arm is of usual construction and has extending laterally therefrom an operating stud 17 which overhangs a finger 18 forming part of a carrier designated generally at C. This carrier is mounted for angular motion on the stud 15 and

a friction plate 19 is held against it by a flat spring 20 engaging a nut 21 on the stud 15. The spring and washer hold the flat body 22 of a carrier C against a hub 23 which may be formed as part of the support 11.

The lay L is provided with a shuttle box B carrying a shuttle S the weft of which will be replenished from the magazine on a weft replenishing beat of the loom. The lay has a bunter 25 which engages a transerrer latch 26 normally in the down position shown in Fig. 1. By

50

means not set forth herein but well understood this latch will be raised into the path of the advancing bunter 25 as the lay moves toward front center position on a weft replenishing beat of the loom and it is in this manner that the trans-
ferrer arm 16 is moved in a counter-clockwise direction around stud 15, Fig. 1, to perform its bobbin transferring operation.

As the trans-
ferrer arm descends its stud 17 engages the finger 18 to rock the carrier C from the normal non-pick-up position shown in Fig. 1 to a pick-up position such as shown for instance in Fig. 7. At a later time a rod 27 rises to engage a wing 28 on the carrier C to restore the latter to its normal position after the trans-
ferrer arm has returned to its normal raised position.

A revoker arm, an example of which is shown at 29, is ordinarily employed to detect whether or not the shuttle is properly positioned for bobbin transfer on replenishing beats of the loom. If the shuttle is in proper position transfer proceeds in ordinary manner, but if the shuttle is misplaced and strikes the revoker arm as the lay advances the latch 26 moves down out of the path of the bunter 25. When the shuttle is widely misplaced the revoker mechanism can be relied upon to prevent transfer, but if the shuttle is only slightly misplaced the revoker mechanism may not always operate with the result that the trans-
ferrer arm will descend while the shuttle is protruding from the box B.

It is to be understood that the type of replenishing mechanism shown in Fig. 1 is set forth merely for the purpose of illustrating the invention and that the matter to be described hereinafter is not limited in its use to the form of magazine M or the type of revoker arm 29 shown. Except as otherwise noted hereinafter the matter thus far described is of common construction.

In carrying the invention into effect there is provided a pneumatic thread-remover designated generally at R including a rigid elongated member, such as tube 35, to the rear end of which, the left as viewed in Fig. 1, is secured a thread deflector or baffle plate 36 fastened at its rear edge to a pneumatic tube 37. The lower end of the latter is formed with a thread pick-up hook 38 which extends downwardly and forwardly with respect to a thread intake mouth 39 at the bottom of tube 37. The latter is connected at its upper end to a hose 40 which leads to any convenient source of subatmospheric pressures.

The carrier C is formed preferably with a laterally extending guide 45 having in the upper end thereof a guide slot 46 defined by the right and left hand walls 47 and 48, respectively, see Fig. 3. Tube 35 normally rests in the lower end of slot 46 and the guide surfaces 47 and 48 permit the tube to move upwardly in slot 46 with respect to the carrier C. A collar 49 is secured to the rigid tube 35 forwardly of the guide 45 as shown in Fig. 1, and a tension spring 50 is operatively interposed between the bottom of the guide 45, as at 51, and the collar, as at 52. The normal effect of spring 50 is to hold the intermediate part of the tube between its ends down in the slot 46.

A sliding pivotal mounting is provided for the forward end of the tube 35 as shown more particularly in Figs. 2, 4 and 5. This mounting comprises a fitting 60 provided with a threaded shank 61 preferably threaded into the forward part of the flat body 22 of the carrier C. A lock nut 62 holds the fitting 60 tightly to the carrier C. Rockable within the fitting 60 is a spherical bearing 65 provided with a cylindrical bore 66 receiv-

ing the forward end of the tube 35. The bearing 65 can oscillate in the fitting 60 to permit angular movement of the rod 35 relatively to carrier C. A compression spring 67 is operatively interposed between the guide 45 and the baffle plate 36 and operates normally to hold the tube 35 in rearward position with the collar 49 against the guide 45.

Normally the parts will be in the position shown in Fig 1 with the remover tube in its raised or thread non-pick-up position. When the trans-
ferrer arm descends its stud 17 engages wing 18 and rocks the carrier C in a counter-clockwise direction, Fig. 1, thereby lowering the guide 45 and the spring 50 causes the tube 35 to move down. If the shuttle is properly placed the tube 37 and the rear parts of the remover will move to a low thread pick-up position, see full lines Fig. 7, in which the tongue or hook 38 will be partly embedded in a mass of deformable material 40, such as plush, secured to the lay below the path of the shuttle. The thread T to be removed extends across the plush 40 and as the lay recedes subsequent to transfer the thread is moved toward the hook and intake mouth, at which time subatmospheric pressures within the tube 37 will attract the thread. It is to be understood that the thread has previously been cut in known manner from the shuttle at a point adjacent to the delivery eye (not shown) of the shuttle S and is therefore free to respond to pneumatic attraction.

If the shuttle should be slightly misplaced the revoker arm 29 may not be effective to prevent a transfer, and the shuttle will project from the shuttle box and be directly under tube 37. The trans-
ferrer arm 16 will descend and rock carrier C as already described. When this has happened in the past damage has generally resulted either to the shuttle or the thread remover, or to both of these parts, but in the present instance the tube 35 when striking the shuttle as indicated for instance in Fig. 6 will move upwardly relatively to the slot 46 and the spring 50 will stretch. In this connection it will be understood that the trans-
ferrer arm exerts a positive force on the carrier C moving it to its pick-up position, see dotted lines, Fig. 6, but the tube 35, having the force of the trans-
ferrer arm transmitted to it by resilient means, is able to remain in engagement with the shuttle as the carrier continues to move. If the remover is engaged by a mis-
placed shuttle as the lay advances the spring 67 will yield to permit tube 35 to slide forwardly in pivotal mounting 60, and spring 50 will stretch to the dotted line position shown in Fig. 7.

While the chief feature of the invention is to prevent breakage of the thread remover in the event that it strikes a misplaced shuttle, it also has a further advantage in that spring 50 can yield slightly if the parts are set so that the bottom of tube 37 and the hook 39 should strike the top of the lay as the carrier C is moved by the trans-
ferrer arm to pick-up position. If the shuttle should be misplaced as already stated and prevent full descent of the member 35 to pick-up position, the rod 27 will restore the carrier to its normal position at a later time, where-
upon the spring 50 restores the member 35 to the bottom of the slot 46 as the parts return to normal thread non-pick-up position.

From the foregoing it will be seen that the invention sets forth a carrier C which is positively moved by the trans-
ferrer arm, but is so formed as to permit relative upward movement of the thread remover R should the latter strike

a misplaced shuttle. Carrier C is formed with a slide guide 45 for the elongated member 35 to permit upward movement of the latter relative to the carrier against the action of spring 50. If for any reason the shuttle S should be behind the thread remover when the latter reaches its low or thread pick-up position the remover will then be pushed forwardly by the misplaced shuttle to the position indicated in dotted lines in Fig. 7. The spring 50 will stretch and permit forward motion of the collar 49, but as soon as the lay moves rearwardly the spring will contract back to its normal position relative to carrier C as shown in full lines in Fig. 7. It will also be seen that should the parts be set in such position that the bottom of tube 37 or hook 39 should touch the top of the lay as the transerrer arm approaches the lower limit of its motion the spring 50 will yield slightly to prevent damage of the thread remover.

Having thus described the invention it will be seen that changes and modifications of the foregoing specific disclosure may be made without departing from the spirit and scope of the invention.

What is claimed as new is:

1. In pneumatic thread remover mechanism for a loom having a bobbin transerrer arm and a supporting stud therefor, a carrier mounted for angular movement on the stud and moved from normal position to pick-up position by the transerrer arm, a thread remover including an elongated member, means mounting the member for pivotal movement with respect to the carrier, a guide for the member on the carrier capable of guiding the member for movement relatively to the carrier in a direction opposite to that in which the carrier moves when moving toward pick-up position, and resilient means normally holding the member in normal position with respect to the carrier but yielding to permit movement of the member relatively to the carrier in said opposite direction when the remover engages a misplaced shuttle as the carrier moves toward pick-up position.

2. In pneumatic thread remover mechanism for a loom, a carrier movably mounted on the loom normally in thread non-pick-up position but moving in a given plane to thread pick-up position incident to a weft replenishing operation of the loom, a thread remover including an elongated member, a pivotal connection between the carrier and the member, a guide on the carrier constructed to permit pivotal motion of the member in said plane relative to the carrier, and means holding the member in normal position relatively to the carrier but permitting said pivotal motion of the member along said guide in the event that the remover engages a misplaced shuttle when the carrier moves to pick-up position.

3. In pneumatic thread remover mechanism for a loom, a carrier mounted on a loom for pivotal movement relatively thereto normally in thread non-pick-up position but moving pivotally to thread pick-up position incident to a weft replenishing operation of the loom, a thread remover including an elongated member, means mounting the member for relative angular move-

ment with respect to the carrier, a guide on the carrier comprising spaced vertical walls along which the member is slideable, and resilient means holding the member in normal position relative to said carrier but yielding to permit angular movement of the member relative to the carrier in the event that the thread remover strikes a misplaced shuttle when the carrier moves to thread pick-up position.

10 4. In pneumatic thread remover mechanism for a loom having a lay, a carrier mounted for movement with respect to the loom normally in thread non-pick-up position but moving to thread pick-up position on weft replenishing

15 beats of the loom, a pneumatic thread remover above the lay including an elongated member, and a pivotal connection between the carrier and the member, the carrier having a vertically extending guide slot through which said member

20 extends and in which said member is movable upwardly with respect to the carrier, said member tending to remain in the bottom of said guide slot and moving upwardly in said slot in the event that the remover strikes a misplaced shuttle when the carrier moves to pick-up position.

25 5. In pneumatic thread remover mechanism for a loom having a lay, a carrier normally in thread non-pick-up position but moving to thread

30 pick-up position incident to a weft replenishing operation of the loom, a pneumatic thread remover including an elongated member, means interconnecting said member and carrier enabling said member to move pivotally and also slide

35 relatively to the carrier, vertical guide means on the carrier along which the member is slideable relatively to the carrier, and resilient means holding said member normally at the bottom of said vertical guide means, said resilient means

40 and carrier effective when the latter moves to thread pick-up position to move the remover downwardly toward the lay and the resilient means yielding to permit upward movement of said member with respect to said guide means

45 in the event that the remover strikes a misplaced shuttle.

6. A carrier and pneumatic thread remover assembly for a weft replenishing loom, said assembly including a carrier adapted for attachment to the loom and including vertical guides, a remover including an elongated member, a pivotal connection between the carrier and member, and resilient means operatively connecting the carrier and member holding the latter in the normal position with respect to the carrier but enabling said member by yielding of the resilient means to move along said guides.
